THREAD SPLICING DEVICE

John F. Cavanagh, Providence, R. I.

Application April 23, 1931, Serial No. 532,351
Renewed April 19, 1935

17 Claims. (Cl. 117—6)

This invention relates to the joining or splicing of yarns, during the various processes involved in the production of yarn and cloth.

I am well aware that the method of uniting the ends of yarns and threads by hand which involves the application of a suitable adhesive or binder to a pair of overlapping thread ends, coincident to the imparting of a rolling motion to said ends, by the fingers, is old and is widely utilized, especially in silk mills. The method has also been used by shoe makers, the binder in this instance being beeswax.

To perform the splicing operation by hand, aside from the exercise of a certain measure of skill, tends toward untidiness, requiring the application of adhesive to the fingers. Another objection to the hand method is the time consumed, which greatly increases the cost over ordinary knotting methods.

My invention has for one of its objects mechanically splicing two threads to replace the hand method.

Another object of the invention is the splicing of the threads in a stronger and better joint than by hand.

A further object of the invention is the splicing of the threads more quickly than may be accomplished by hand and yet preserve the better quality of splice.

With these and other objects and advantageous features in view, the invention consists of a novel arrangement of parts more fully disclosed in the detailed description following, in conjunction with the accompanying drawing, and more particularly set forth in the appended claims.

Fig. 1 is a perspective view of my device;

Fig. 2 is a central section, showing the mechanism in its normal state of rest;

Fig. 3 is a detail, showing the relative positions of the splicing members upon completion of a splice;

Fig. 4 is a front elevation of the thread gripping device;

Fig. 5 is a plan view showing the splicing members and thread gripper with threads in place ready to be spliced;

Fig. 6 is an enlarged view of a completed splice.

Referring to the drawing, 10 is a casing which acts as a frame to support the parts and to which is secured stationary splicing member 11.

For reciprocating contact with said splicing member 11, a sliding splicing member 12 is mounted upon a carriage plate 13, and moved upwardly by handle 14 pivoted intermediate its

ends about the rod 39 through suitable links 40 connecting the handle and carriage 13. A jaw 16, of a thread gripper is mounted at the upper end of a resilient spring arm 15 which in turn carries slide 17, upon which is mounted a co-operating thread gripping jaw 18 held normally against the jaw 16, by leaf spring 19. Slide 17 is provided at its upper end with thread guides 20 and 21, and also carries cross bar 22 for a purpose to be explained. A torsional spring 23 encircling the rod 39 holds the handle 14 normally in the position shown while the mechanism is retained in its position of rest, shown in Fig. 2.

The lower part of carriage plate 13 carries a rearwardly projecting rib 41 having a cam surface 24 for engagement with stud 25 mounted on the casing for the purpose of separating splicing members 11 and 12 as shown in Fig. 2 for the reception of threads to be spliced. The upper end of the rib 41 is provided with a hook 26 for the purpose of engaging cross bar 22 for moving and thus holding the jaws 16 and 18 normally separated against the tension of a spring 19. The lower end of carriage 13 is provided with a foot 27 for engaging slide 17 and causing the carriage 25 plate 13 to tilt in its upper position for the purpose of opening splicing members 11 and 12 as shown in Fig. 3. A cam surface 28 on rib 41 engaging with cross bar 22 forces both jaws of the entire thread gripper mechanism outward as said carriage 13 moves upward, through the flexing of spring 15 whereby the yarn is broken at the sharpened edge 42 with frayed ends.

Mounted upon the back of casing 10 is elbow 29 provided with a duct leading through splicing member 11 as at 30 and also provided with a suitable check valve 31. A similar elbow 32 and likewise provided with a check valve 33 is mounted at the bottom of casing 10 while the two elbows are connected by a resilient rubber tube 34.

A wire loop 35 is connected to handle 14 at a point spaced from the pivot so that it will move and compress the rubber tube 34 when handle 14 is operated. This arrangement of tube 34 with elbows 29 and 32 constitute a syringe-like pump to force liquid placed in the reservoir 43 in the lower part of casing 10 to be delivered in small quantities to the upper part of splicing member 11 through the functioning of check valves 31 and 33 and the operation of compression member 35.

In operating my device, a quantity of suitable liquid adhesive or binder is placed in the reservoir 43 and handle 14 is operated a few times to start circulation to the splicing members 11 and 12.

It will be noted that the upper portion of splicing member 12 is narrower than the body and is provided with bevelled or sharp edges, as shown in Fig. 5 and I preferably make splicing members 11 and 12 from vitreous material, such as lava or some of the artificial abrasive stones, having a high co-efficient of friction and also serving to retain liquid.

In operation, my device is held in one hand with the thumb across handle 14. The other hand is utilized to first pass the end of yarn 36 between splicing members 11 and 12 around edge of splicing member 12 under guide 21 and between jaws 16 and 18 permitting the free end to fall as shown in Fig. 1. The other yarn 37 is likewise positioned from the opposite side. Handle 14 is then depressed and the carriage 13 and splicing member 12 moves upward pressing the pair of yarns under action of spring 15 through the rib 41 snugly between splicing members 11 and 12. Upon the first upward movement of carriage 13 jaw 18 is permitted to move upward under action of spring 19 binding the pair of yarn ends and due to the action of cam surface 28 the jaws are forced back causing the yarns to be broken where they cross the edge of splicing member 12 by being pulled apart and thus leaving a frayed end. Binder liquid is co-incidentally being applied to the yarns while splicing members 11 and 12 roll the overlapping yarns into a close and even splice with ends tapered after which the members 11 and 12 move apart as shown in Fig. 3 to permit the work to be removed. Upon the return of the mechanism through the action of spring 23 to its position of rest, shown in Fig. 2, the severed ends may be removed from between jaws 16 and 18. I find that this latter operation is not necessary until several pairs of ends are involved.

In the making of yarn splices I find that it is important that the ends to be united be frayed, that is, the fibers should be of varying length such as produced by breaking the yarn as opposed to cutting it squarely across. I have discovered that stressing a piece of yarn across the sharp edge of an abrasive stone causes the yarn to sever invariably producing a frayed condition and I have embodied this principle of severing in this device.

Yarn ends, thus prepared, will "tuck in" and intertwine much more effectively than squarely sheared ends, and reference to Fig. 6 will make clear the tapered effect produced. The center of the splice is slightly larger than the diameter of the original thread, while the frayed ends insure a taper between the two diameters as at 38 rather than an abrupt change. Furthermore, the fibrous ends make for greater strength and hold more securely than would be the case with sheared ends.

The foregoing description is directed solely towards the construction illustrated, but I desire it to be understood that I reserve the privilege of resorting to all the mechanical changes to which the device is susceptible, the invention being defined and limited only by the terms of the appended claims.

I claim:

1. In a thread splicing device, means for gripping a pair of ends at spaced points and moving the gripping points apart to break the ends to provide a frayed condition, and means for rolling the end portions of the threads to be joined one about the other.

2. In a thread splicing device, means for sever-

ing a pair of ends and means for rolling the end portions of the threads to be joined one about the other comprising bodily relatively reciprocating members movable in a straight line.

3. In a thread splicing device, means for severing a pair of ends, means for rolling the end portions of the threads to be joined one about the other between a pair of relatively bodily moving members, and means for causing adhesive to flow between said moving members to moisten the thread end portion as rolled movable in a straight line.

4. In a thread splicing device, relatively reciprocating thread rolling members, thread gripping jaws, means for causing said members to nip a pair of thread ends placed therebetween and at substantially the same time, said jaws to grip the thread ends and then subsequently move from said members to break the thread.

5. In a thread splicing device, a frame support, a fixed thread rolling member mounted therein, a movable thread rolling member, a relatively fixed jaw resiliently mounted in said frame, a movable jaw slidable along the resilient mount of the fixed jaw, a lever handle mounted in said support, a carriage for said movable thread rolling member, a cam surface provided thereon engaging said resiliently mounted fixed jaw, a spring for causing said jaws to move together and said carriage to move upwardly on movement of said handle, said cam being shaped to cause said jaws to move from said members to break the thread as said members to move one along the other and roll the thread end portions, a reservoir provided on said frame, a flexible conduit causing communication of said reservoir and the surface of said element, and a pressure member engaging said flexible conduit and operated by said handle lever for pumping liquid from said reservoir to the surface of said elements.

6. In a thread splicing device bodily relatively reciprocating thread rolling members movable in a straight line, manually movable means for operating said members and means for moving said thread rolling members apart at the start of the relatively reciprocating stroke of said members whereby the work may be easily positioned between said member.

7. In a thread splicing device bodily relatively reciprocating thread rolling members movable in a straight line, manually movable means for operating said members and means for moving said thread rolling members apart at the end of the relative reciprocating stroke of said members for easy removal of the work.

8. In a thread splicing device bodily relatively reciprocating thread rolling members, manually movable means for operating said members and means for moving said thread rolling members apart at the start and finish of the relatively reciprocating stroke of said members whereby the work may be easily positioned and withdrawn from between said member.

9. In a thread splicing device, means for gripping the threads of a pair of ends at spaced points and moving the gripping means apart to pull the threads apart, and means for rolling the end portions of the threads to be joined one about the other.

10. In a thread splicing device, a rolling member having an edge, means for gripping a pair of ends at spaced points and pulling them both over an edge of said member to break them, and means for rolling the end portions of the threads to be joined one about the other.

5 11. In a thread splicing device, a rolling member having an edge, means for gripping a pair of ends at spaced points and pulling them over an edge of said member to break them, means for rolling the end portions of the threads to be joined one about the other, and means for applying adhesive to the thread end portions as rolled.

10 12. In a thread splicing device, relatively reciprocating thread rolling members, thread gripping jaws, a manually operated lever, and means responsive to the movement of said lever for causing relative movement of the members to first nip the thread then cause a relative movement apart of said members and jaws to break the thread at a predetermined point and subsequently roll the end portions of the thread one about the other.

15 13. In a thread splicing device, relatively reciprocating thread rolling members, thread gripping jaws, a manually operated lever, and means responsive to the movement of said lever for causing relative movement of the members to first nip the thread and then cause a relative movement apart of said members and jaws to break the thread at a predetermined point with frayed ends and subsequently to relatively move the members to roll the end portions of the thread one about the other.

20 14. In a thread splicing device, relatively reciprocating thread rolling members, thread gripping jaws, a manually operated lever, means responsive to the movement of said lever for causing relative movement of the members to first nip the thread and then cause relative movement apart of said members and jaws to break the thread and subsequently roll the end portions of the thread one about the other, and

means for applying adhesive to the thread ends as rolled.

25 15. In a thread splicing device, relatively reciprocating thread rolling members, thread gripping jaws, a manually operated lever, means responsive to the movement of said lever for causing relative movement of the elements to first nip the thread and then cause a relative movement apart of said members and jaws to break the thread at a predetermined point and subsequently 10 relatively move the members to roll the end portions one about the other, and means operated by said handle for applying adhesive to the thread ends as rolled.

15 16. In a thread splicing device, a frame support, a fixed thread rolling member mounted therein, a movable thread rolling member, a relatively fixed jaw resiliently mounted in said frame, a movable jaw slidable along the resilient mounting of the fixed jaw, a lever mounted in 20 said frame support, a carriage for said movable thread rolling member, a cam surface carried thereby for engaging said resiliently mounted fixed jaw, a spring for causing said jaws to move together, a handle pivoted on said frame support, 25 links connecting said carriage and handle to cause said carriage to move upwardly on movement of said handle, said cam being shaped to cause said jaws to move from said fixed and movable thread rolling members to break the 30 thread, and said rolling members to move one along the other to roll the thread end portions.

35 17. In a thread splicing device, means for pulling apart the threads of a pair of ends at a predetermined point to provide frayed ends, and means for rolling the end portions of the threads to be joined one about the other.

JOHN F. CAVANAGH.
